By Gen. Princip.

UNITED STATES PATENT OFFICE.

ALBERT H. NORTH, OF BRIDGEPORT, CONNECTICUT.

CARVING-FORK GUARD.

SPECIFICATION forming part of Letters Patent No. 317,842, dated May 12, 1885.

Application filed June 11, 1884. (No model.)

To all whom it may concern:

Be it known that I, ALBERT H. NORTH, a citizen of the United States, and a resident of Bridgeport, in the county of Fairfield and State of Connecticut, have invented certain new and useful Improvements in Cutlery, of which the following is a specification.

The object of my invention is to provide a carving-fork with an adjustable guard and rest, so arranged and constructed that they may be brought into any desired position in relation to the fork, and when required the guard and rest may be made to conform so nearly to the shape of the fork as to greatly facilitate packing for shipment.

My invention consists of an ordinary carving-fork with either a flat or round shank and having a hole diagonally through the shank at the proper angle to receive the guard and rest, the guard having one end threaded and the rest having threaded hole to receive the guard, by means of which the guard and rest, operating as bolt and nut, are firmly secured to the shank of the fork.

Heretofore adjustable guards have been made having springs or pins to hold them in the proper position, and these require elongated holes or slots in the shank, making a complicated arrangement, besides leaving receptacles for the dirt to lodge.

To more clearly understand my invention, reference is had to the drawings, and to the figures and letters of reference marked thereon.

Figure 1 represents a side elevation of the fork having a round shank. Fig. 2 represents a broken view through the dotted lines 1 2 of Fig. 1. Fig. 3 represents a broken view through the dotted lines 1 2 of Fig. 1, also a broken sectional view of the shank. Fig. 4 represents a front elevation of the guard and rest. Fig. 5 represents the guard and rest as applied to a fork having a flat shank.

Its construction and operation is as follows: A is the shank; B, the guard; C, the rest. D represents the tines; E, the handle. a is a hole formed diagonally through the shank; b c, enlarged openings for the guard and rest.

The hole a (see Fig. 3) passes diagonally through the body of the shank A, so that the bottom d d' of the recesses b c will stand at the proper angle.

The guard B (see Fig. 2) has the reduced

threaded end e, which enters freely the hole a of the shank A. (See Fig. 3.) The base f of the guard B enters the recess b. The head or boss g of the rest C enters the recess c, and has a threaded hole to receive the end e of the guard. The bottom of the base f of the guard and the top g of the rest are, by means of the threaded parts, brought firmly against the bottom of recesses b c, and the angle at which d d' stands, together with the proper form and shape of the guard and rest, will determine their different positions. When required to pack for shipment, the guard and rest will be in the position as indicated by Figs. 1 and 2. The guard B will be brought down on a line with the tines and the rest carried back on a line with the shank, thus occupying but little if any more space than the fork alone. When necessary to use the guard, the rest C is turned to the right and the guard B to the left until they assume the dotted position, as seen at Fig. 1. The operation of turning the guard and rest to the right and left will be properly timed, so that they will be firmly seated when brought into either of the positions shown.

The rest has the two prongs or legs C C', as seen at Fig. 4, to support the fork. Any design for the guard or rest or that part projecting from the shank may be employed that will be most desirable for the style of fork on which they may be used.

When required to use the device on a fork having a flat shank, the proper angle is obtained by the bend or offset h. (See Fig. 5.) One straight hole through the shank h for the end e of the guard is all that is necessary. The base of the guard and rest abut against each side of the shank h, the operation and result being the same in both styles of forks. Its simplicity, combined with strength, cheapness of manufacture, and ready means of adjustment, and the facility it offers for packing, gives it a decided advantage over other forks of this class now in use.

I am aware that forks have been made provided with a reversible guard and rest, the shank of the guard operating within a diagonal hole through the shank of the fork, the guard and rest held in place by spring pressure.

What I claim as new, and desire to secure by Letters Patent, is—

1. In a carving-fork, the combination, with the shank having a hole situated through the same, of a guard having a threaded end and a rest having a threaded hole to receive the threaded end of the guard, by means of which the guard and rest are held firm and rigid to the shank, substantially as set forth.

2. The shank A, having hole *a*, situated diagonally therein, and recesses *b c*, in combination with the guard B, having threaded end *e*,

and rest C, having threaded hole to receive the guard, all substantially as described, and for the purpose set forth.

Signed at Bridgeport, in the county of Fairfield and State of Connecticut, this 7th day of 15 June, A. D. 1884.

ALBERT H. NORTH.
